UNITED STATES PATENT OFFICE.

ALPHEUS DARLING AND JOSEPH DARLING, OF PETROLIA, PENNSYLVANIA,

GOVERNOR FOR CONTROLLING THE SUPPLY OF FLUIDS.

SPECIFICATION forming part of Letters Patent No. 357,763, dated February 15, 1890.

Application filed August 7, 1888. Serial No. 219,265. (No model.)

To all whom it may concern:

Be it known that we, ALPHEUS DARLING and JOSEPH DARLING, both of Petrolia, in the county of Butler and State of Pennsylvania, have invented a new and Improved Governor for Controlling the Supply of Fluids, of which the following is a full, clear, and exact description.

Our invention relates to governors of that class used for regulating the supply of gaseous fuel to steam-boilers or for regulating the pressure of steam or other fluids at a point of delivery, and has for its object to provide a simple, efficient, and durable governor of this character.

The invention consists in certain novel features of construction and combinations of parts of the governor, all as hereinafter fully described and claimed.

Reference is to be had to the accompanying drawings, forming a part of this specification, in which similar letters of reference indicate corresponding parts in all the figures.

Figure 1 is a side elevation showing our improved governor applied to use for regulating the supply of gaseous fuel to a steam-boiler. Fig. 2 is a central longitudinal sectional elevation of the governor as arranged with one valve at each end opening to opposite ports connected with the fluid-supply and waste-outlet, respectively. Fig. 3 is a central longitudinal sectional elevation of a governor as arranged with two valves at each end opening to opposite ports connected with the fluid-supply and waste-outlet; and Fig. 4 is a transverse sectional plan view taken on the line $x-x$, Fig. 3, with the auxiliary valve partly broken away.

Referring first to Fig. 2 of the drawings, it will be seen that the case A of the governor is centrally chambered at B, and at one side has an inlet-port, C, opening into this chamber, and around which a nipple, c, projects from the case for the attachment of a pipe, D, leading from the oil or gas well to convey the gas to the chamber B of the case. At opposite ends the case A is provided with passages or supply and waste-ports E F, formed around the case and extending inward from each end of the case, and these ports have outlets at E' F', respectively, around which screw-nipples

e f are provided for the attachment of pipes G H, respectively, the pipe G leading to the furnace of the boiler I, as in Fig. 1, and the pipe H serving to conduct the waste or excess of gas to a storage-reservoir, (not shown,) or it may be to a distant place of discharge into the open air.

A spindle or stem, J, passing lengthwise through the chamber B of case A, is connected at opposite ends with flexible diaphragms K L, respectively, which are clamped tightly at their margins between the ends of the case A, outside of the adjacent ports E F, and the end caps, M N, of the case by screws m n, or otherwise. The diaphragms are adapted to be pressed close to the ends k l of the walls of the chamber B inside of the ports E F, these ends or seats k l for the valve-diaphragms K L being preferably a little inside or back of the plane of the outer end parts of the case A, to which the diaphragms are clamped.

The valve-diaphragms K L are made, preferably, of rubber or like elastic fabric, and when it is preferred to have the diaphragms close directly onto the seats k l the metal plates K' L', held next the diaphragms by the nuts or collars k' l' on the ends of the stem J, will be placed outside of the diaphragms, as shown; but when it may be preferable to have metal seat upon metal the plates K' L' will be placed at the outer faces of the diaphragms, so that they will close directly on the seats k l of the case, as will readily be understood. The plates K' L' have a diameter or marginal size about corresponding with the inner walls of the ports E F, so as to give an effective closure of the ports.

Next to one end of the valve-stem J there is secured at its margin, about at the center of the cap M, and by screws o, a diaphragm, O, which provides a chamber, P, above it in the cap, and an outlet, F', from said chamber is surrounded by a screw-nipple, p, to which a pipe, R, may be attached, said pipe R leading to the steam-drum or steam-space of the boiler I, as shown in Fig. 1.

Beneath the spindle J or its nut or collar k there is placed, in a pendent tubular stem M' of the cap N, a spiral spring, S, the lower end of which rests on a presser-block, T, which

may be forced inward to regulate the pressure of the spring on the diaphragm L next the waste-port F of the case A by a screw, U, threaded into the end of the cap-stem N'. (See Fig. 2.)

The operation is as follows: The tension of the spring S will be regulated by the screw U to hold the diaphragm L to its seat l and hold the diaphragm K away from its seat k, to allow a proper quantity of gas to pass from the chamber B, port E, and outlet E', as indicated by the arrows in Fig. 2, and through the pipe G to the boiler-furnace at any desired predetermined pressure of steam to be maintained in the boiler. Should the boiler-pressure rise above this normal limit, the steam-pressure through pipe R on the diaphragm O will depress the valve-stem J and close the diaphragm K partly or wholly to its seat k, and thereby cut off the excessive supply of gas to the boiler-furnace, and at the same time the stem J will depress the diaphragm L and open the port F to the chamber B, to allow the gas to escape or waste at the outlet F' through the pipe H, and thus prevent the backing up of gas-pressure in the supply-pipe D. When the steam-pressure lowers to the normal limit, the spring S will expand to close the diaphragm L to its seat l and cut off the waste of gas, and the diaphragm O will simultaneously be opened, to allow gas to again pass to the boiler-furnace, as above described. The valve-stem J and diaphragm-valves K L may be so arranged that a proper supply of gas will pass to the furnace, while the excess of gas coming under pressure through the pipe D will be allowed to escape at the waste-outlet F'.

It is obvious that the diaphragms K L not only act as valves to pass the gas to the furnace and to waste, but the diaphragms serve as partitions which entirely cut off the gas from the spaces at the ends of the case A, in which the diaphragm O and spring S are placed; hence these parts O S cannot be affected by the gas, and will respond very sensitively to changes in the steam-pressure, whereby said pressure may be closely controlled.

Another important feature of this construction of the governor is, that the diaphragms K L open all around their respective seats k l, and give a prompt full exit or passage of gas with a very slight movement of the diaphragm, and this prompt opening and closure of the opposite diaphragms K L by a slight movement of them materially increases or improves the sensitiveness of the governor, and also allows a much less bulky governor to perform the work of a larger more expensive one otherwise arranged.

The distinctive features of our invention may easily be embodied in a governor having two or more diaphragm-valves controlling ports opening to a common outlet at opposite ends of the governor-case, and as shown in Figs. 3 and 4 of the drawings, wherein the

valves K L on a stem, J, are acted on by a steam-pressed diaphragm, O, as above described; but instead of the spring S we show a counterbalance-weight, s, on an arm or lever, s', connected with the valve-stem J, which projects through a stuffing-box, N', on the lower cap, N, for utilizing the gravity of the weight to counteract the pressure on the diaphragm O. These valves K L are seated at k l, like the valves K L in Fig. 2.

On the valve-stem J, and at short distances from the valves K L, there are fixed the valves K' L', respectively, which are adapted to close on seats k' l', formed at the open ends of annular ports E' F', which are formed in contracted portions of the case A, and open also into the outlets E' F', respectively. These valves or diaphragms K' L' consist preferably of two plates—one of rubber, the other of metal—and are perforated, as at k' l', respectively, so that gas or other fluid may freely pass through them to the imperforate outer diaphragm-valves, K L, to escape past the seats k l into ports E F, while the fluid is escaping past the seats k' l' into the ports E' F', thus assuring a perfect balance of the opposite pairs of valves, and allowing a much quicker opening for escape of the gas or other fluid to the ports E' F' of the governor.

In Fig. 3 the lower valves, L L', are open for exit of gas at the waste-outlet F, and the upper valves, K K', are closed, as when excessive pressure of steam in the boiler on the diaphragm O has cut off the supply of gas to the boiler through the outlet E, the passage of the gas through the open valves being indicated by the arrows.

It is obvious that three or more valves may be arranged at each end of the governor in a suitably-contracted case; and in every instance all the valves except the outer ones, K L, will be perforated for the passage of the gas or fluid to secure a balance of the entire valve system, as above explained.

This governor may be used for reducing the pressure of steam to insure a regular pressure at a point of delivery as well as for supplying gaseous fuel to furnaces, as herein more particularly described.

Having thus fully described our invention, we claim as new and desire to secure by Letters Patent—

1. A governor for controlling the supply of fluids, constructed with a chambered case having an inlet and with two outlets, one for fluid-supply and the other for waste, and diaphragm-valves adapted to seats in the case and controlling the supply and waste outlets, and said valves clamped marginally to confine the fluid between them and allow it to pass to the supply and waste outlets, substantially as described, for the purposes set forth.

2. A governor for controlling the supply of fluids, constructed with a chambered case having an inlet and with two outlets, one for fluid-supply and the other for waste, a valve-

stem traversing the case-chamber, and diaphragm-valves adapted to seats in the case and attached to the opposite ends of the stem and clamped marginally at the ends of the case, 5 to confine the fluid between them and allow the fluid to pass to the supply and waste outlets, substantially as described, for the purposes set forth.

3. A governor for controlling the supply of fluids, constructed with a chambered case having an inlet and with two outlets, one for fluid-supply and the other for waste, ports ranging around the opposite ends of the case and communicating with the supply and waste outlets, respectively, a valve-stem traversing the case-chamber, and diaphragm-valves adapted to seats in the case and attached at opposite ends of the stem and clamped marginally at the ends of the case, to confine the fluid between them and allow it to pass to the supply and waste outlets, substantially as described, for the purposes set forth.

4. A governor for controlling the supply of fluids, constructed with a chambered case having an inlet and with two outlets, one for fluid-supply and the other for waste, ports at opposite ends of the case communicating with the supply and waste outlets, respectively, a valve-stem traversing the case-chamber, diaphragm-valves adapted to seats in the case to control the supply and waste outlets and attached to the stem, and said valves clamped marginally to confine the fluid between them, a diaphragm open to exterior pressure at one end of the case and adapted to operate the diaphragm-valves, and a spring or counter-acting device resisting the movement of the valves by the pressed diaphragm, substantially as described, for the purposes set forth.

49. 5. The combination, in a governor for controlling the supply of fluids, of a case, A, chambered at B and provided with an inlet, C, outlets E' F', and ports E E' F F', a valve-stem, J, imperforate diaphragm-valves K L, fixed to stem J and clamped between the case-caps M and N and the body of the case and controlling ports E F, respectively, and auxiliary perforated valves K' L', fixed to stem J and controlling the ports E' F', a diaphragm, O, in a chamber, P, and open to fluid-pressure, and a device acting on the stem J to resist the movement of the valves by the pressure of the diaphragm O, substantially as described, for the purposes set forth.

between the case-caps M and N and the ends 45 of the body of the case, and adapted to seats k l in the case and attached to stem J, a diaphragm, O, in a chamber, P, at one end of the case and having an inlet at P' for passage of fluid under pressure, and a spring or counter-acting device at the other end of the valve-stem J, substantially as herein set forth.

6. A governor for controlling the supply of fluids, constructed with a chambered case having an inlet and with two outlets, one for fluid-supply and the other for waste, imperforate main diaphragm-valves adapted to seats in the case and controlling ports at opposite ends of the case and clamped marginally in the case to confine the gas or fluid between them and allow it to pass to the supply and waste outlets of the case, and one or more perforated auxiliary valves fitted on the same stem with the main diaphragm-valves and controlling independent ports formed in the case, 65 and communicating with the supply and waste outlets, substantially as described, for the purposes set forth.

7. The combination, in a governor for controlling the supply of fluids, of a case, A, 70 chambered at B and provided with an inlet, C, outlets E' F', and ports E E' F F', a valve-stem, J, imperforate diaphragm-valves K L, fixed to stem J and clamped between the case-caps M and N and the body of the case and 75 controlling ports E F, respectively, and auxiliary perforated valves K' L', fixed to stem J and controlling the ports E' F', a diaphragm, O, in a chamber, P, and open to fluid-pressure, and a device acting on the stem J to resist the 80 movement of the valves by the pressure of the diaphragm O, substantially as described, for the purposes set forth.
